CLAIM

The ornamental design for a bottle, as shown and described.

DESCRIPTION

FIG. 1 is an elevational view of the front of the bottle showing the new design;

FIG. 2 is a top and front perspective view thereof;

FIG. 3 is a bottom plan view thereof;

FIG. 4 is an enlarged cross sectional view of a portion of FIG. 1 illustrating the central hub shown in FIG. 3 and its upwardly extending construction; and,

FIG. 5 is a top plan view thereof.

The rear and side elevations of the bottle are the same as the front view shown in FIG. 1 except for the neck finish and the orientation of the feet on the base.

The portion of the bottle neck that is not shown in the drawings does not form a part of the claimed design.
